Primary Examiner — Clare E Heflin(74) *Attorney, Agent, or Firm* — Michael Best & Friedrich, LLP**CLAIM**

The ornamental design for a lighting fixture having struts, as shown and described.

DESCRIPTION

FIG. 1 is a top plan view of a lighting fixture having struts according to a first embodiment of the invention;

FIG. 2 is a top perspective view of the lighting fixture illustrated in FIG. 1;

FIG. 3 is a front elevational view of the lighting fixture illustrated in FIGS. 1 and 2, the back elevational view being the mirror image thereof;

FIG. 4 is a left side elevational view of the lighting fixture illustrated in FIGS. 1-3, the right side being the mirror image thereof;

FIG. 5 is a bottom plan view of the lighting fixture illustrated in FIGS. 1-4; and,

FIG. 6 is a bottom perspective view of the lighting fixture illustrated in FIGS. 1-5.

1 Claim, 3 Drawing Sheets(56)
